(57) **CLAIM**

The ornamental design for a flashlight having tail lights, substantially as shown and described.

DESCRIPTION

FIG. 1 is a perspective view of the ornamental design for a flashlight having tail lights;

FIG. 2 is a second perspective view of the ornamental design of FIG. 1;

FIG. 3 is a side view of a first side of the ornamental design of FIG. 1, of which the opposite side is a mirror image;

FIG. 4 is a side view of a second side of the ornamental design of FIG. 1;

FIG. 5 is a side view of a third side of the ornamental design of FIG. 1;

FIG. 6 is an end view of a first end of the ornamental design of FIG. 1; and,

FIG. 7 is an end view of a second end of the ornamental design of FIG. 1.

The broken line showing in the drawings is included for the purpose of illustrating portions of the flashlight having tail lights and forms no part of the claimed design.

1 Claim, 5 Drawing Sheets
